ATTORNEY

UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 35,781, dated March 4, 1902.

Application filed February 7, 1902. Serial No. 93,088. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part thereof.

In the said drawings, Figure 1 is a plan view of a plate with my design thereon. Fig. 2 is a vertical cross-section of the same.

The centerpiece *a* consists of a leafed ornament of approximately triangular form. From either side of this centerpiece proceeds a combined stem and leafed ornament *b* in

the form of a reversed curve and having spiral branches *c* and terminals *d*. This ornament is supplemented by a similar ornament *e*, terminating in a spiral *f*. This ornamentation is repeated a number of times to form a continuous border.

What I claim is—

The design for a plate or similar article substantially as herein shown and described.

Signed at the city of New York, in the county of New York, this 29th day of January, 1902.

CHARLES J. AHRENFELDT.

Witnesses:

M. D. DOERING,
WILLIAM R. BAIRD.
